UNITED STATES PATENT OFFICE.

EDWIN NORTON, OF MAYWOOD, ILLINOIS, ASSIGNOR TO THE AUTOMATIC VACUUM CANNING COMPANY, OF CHICAGO, ILLINOIS.

VACUUM-SEALING JAR.

SPECIFICATION forming part of Letters Patent No. 681,130, dated August 20, 1901.

Application filed November 3, 1900. Serial No. 35,318. (No model.)

To all whom it may concern:

Be it known that I, EDWIN NORTON, a citizen of the United States, residing in Maywood, in the county of Cook and State of Illinois, have invented a new and useful Improvement in Vacuum-Sealing Jars, of which the following is a specification.

My invention relates to vacuum-sealing preserving-jars.

It consists in a preserving-jar, of glass or other suitable material, having an external shoulder, a seaming-ring having an internal shoulder, a packing between said shoulders, an inturned flange at the lower edge of the seaming-ring compressing the packing between said shoulders and hermetically sealing and locking the seaming-ring to the jar, a flange at the upper edge of the seaming-ring, and a cover having a packing, a flange or seat for the packing, and a rim or flange folded into a double seam with the flange on the seaming-ring to firmly compress the packing between the cover and seaming-ring and lock and secure together the ring and cover with great strength, tightness, and rigidity and securely confine the packing within and by the folds of the double seam, so that after the cover has been sealed to the jar in vacuum by a vacuum or atmospheric-pressure seal and the cover further secured to the seaming-ring by the double seam the contents of the sealed can may be subjected to any required cooking operation without danger of the steam-pressure thus generated within the sealed can loosening the cover or breaking or rendering defective the packed seam or joint between the ring and cover.

In the accompanying drawings, forming a part of this specification, Figure 1 is a central vertical sectional view showing the top portion or neck of a vacuum-sealing preserving-jar embodying my invention with the cover loosely in place thereon and ready to be sealed and secured thereto by a vacuum or atmospheric-pressure seal by placing the filled jar within the receiver of a vacuum-pump, exhausting the air therefrom, and again admitting the air to the receiver. Fig. 2 is a similar view showing the cover sealed and secured to the jar by a vacuum or atmospheric-pressure seal, and Fig. 3 is a simi-

lar view showing the flanges of the cover and seaming-ring of the vacuum-sealed jar double-seamed together.

In the drawings, A represents the jar; a, the external shoulder on its neck; B, the seaming-ring; b, its internal shoulder; C, the packing between said shoulders a and b, and b', the inturned flange at the lower edge of the seaming-ring, locking the ring to the jar and compressing the packing C, so as to hermetically seal and secure the ring to the jar. The seaming-ring B has a lateral flange b² at its upper edge, forming a smooth shoulder for compressing the packing F, which is interposed between the ring B and cover D. The cover D has a flange or shoulder d, surrounded by the packing F, and a seaming-rim d', which is folded into a double seam d² with said flange b² on the ring B, thus rigidly and unyieldingly compressing and confining the packing F within and by the folds of said double seam and securely uniting the cover to the seaming-ring. Protecting-disks G and g are interposed between the cover D and the upper face a' of the jar-mouth to prevent the contents of the jar from coming in contact with the sheet-metal cover D or seaming-ring B.

In operation, after the cover of the filled preserving-jar has been sealed and secured thereto in vacuum by a vacuum or atmospheric-pressure seal, as illustrated in Fig. 2, the sealed jar is removed from the receiver of the air-pump and placed in a double-seaming machine of any suitable or customary construction and the flanges d' and b² formed into a double seam d², thus rigidly uniting the two and tightly compressing and confining the packing F between the cover and seaming-ring and the folds of said double seam. The vacuum or atmospheric-pressure seal, as illustrated in Figs. 2 and 3, collapses or inwardly curves the flexible sheet-metal cover D, owing to the vacuum within the jar and the atmospheric pressure outside thereof.

I claim—

1. The vacuum-sealing preserving-jar comprising in combination a jar having an external shoulder, a seaming-ring having an internal shoulder, a packing between said shoulders, an inturned flange at the lower edge of

- said seaming-ring compressing said packing and locking and hermetically sealing said ring to said jar, a flange at the upper edge of said ring, a cover having a flange or shoulder, a packing thereon and a seaming-rim and a double seam formed by folds in said rim of the cover and said flange at the upper edge of the seaming-ring, substantially as specified.
10. 2. The combination with a jar, of a seaming-ring hermetically sealed and secured to the said jar, a cover, a packing between the cover and seaming-ring, said cover being hermetically sealed and secured to said seaming-ring by a vacuum or atmospheric-pressure seal collapsing or inwardly curving said cover and a double seam locking and securing the cover to the seaming-ring and firmly compressing and confining the packing between the cover and ring, substantially as specified.
15. 3. The vacuum-sealed preserving-jar comprising in combination jar A having shoulder a , packing C, seaming-ring B having shoulder b , flanges b' and b'' , and cover D having flange or shoulder d , rim d' , packing F and
20. 25. flange or shoulder d , rim d' , packing F and

double seam d^2 uniting said cover and ring, substantially as specified.

4. The vacuum-sealed preserving-jar comprising in combination jar A having shoulder a , packing C, seaming-ring B having shoulder b , flanges b' and b'' , and cover D having flange or shoulder d , rim d' , packing F and double seam d^2 uniting said cover and ring, and a protecting-disk between the jar and cover, substantially as specified. 30

5. The vacuum-sealed preserving-jar comprising a jar A, seaming-ring B hermetically sealed and secured to said jar by a packed joint, a cover D having a packed joint between it and the seaming-ring and hermetically sealed and secured thereto by a vacuum or atmospheric-pressure seal and a double seam additionally securing together the cover and seaming-ring and confining the packing between the same, substantially as specified. 35 40 45

EDWIN NORTON.
